MECHANICAL FLASHLIGHT

Henry Weil, Goldsboro, N. C.

Application May 3, 1944, Serial No. 533,849

1 Claim. (Cl. 240—10.5)

The present invention relates to self-generating flashlights.

The principal object of the invention is to provide a self-generating flashlight having the means to produce either a relatively weak current of electricity for a relatively long period of time or a relatively strong current for a relatively short period of time.

Another object is to provide a self-generating flashlight having the capacity and means to produce a relatively strong beam of light as well as a relatively weak beam of light.

The advantages of such self-generating flashlight are clear. There are times when it is desirable to have a long continuing supply of light irrespective of its intensity. At other times a beam of light of relatively high intensity is needed, without particular regard to the length of time such beam of light would be available.

These and other objects are attained by mechanism illustrated in the accompanying drawing in which

Figure 1 is a vertical section on the line 1—1 of Fig. 2 of the entire mechanism said section being on a plane parallel with the plane of its wide sides;

Figure 2 is a vertical section of the entire mechanism on the line 2—2 of Figure 1, said view being on a plane parallel with the plane of its narrow sides;

Figure 3 is a horizontal section of the entire mechanism on a plane parallel with the plane of its top and bottom ends;

Figure 4 is a sectional view of the combination gear speed changer and electric switch; and

Figure 5 is a sectional view, on a plane perpendicular to the plane of the view in Figure 4, of the same device there shown, showing, diagrammatically, the place of said device in the electric circuit of the entire mechanism.

The self-generating flashlight herein disclosed consists, essentially, of a casing 10, a spring motor 11, a dynamo 12, a gear train 13 connecting said motor with said dynamo and providing for a high speed differential between said motor and said dynamo in favor of the dynamo, a pair of flashlight bulbs of different voltage, the smaller bulb being designated 14 and the larger 15, a combination gear speed changer, and electric switch 16 and electric wiring 17 interconnecting said dynamo, bulbs and switching device. The casing 10 houses all of the other parts of the flashlight hereinabove listed.

The spring motor 11 is affixed to the casing 10 in the usual manner. Key 18, when turned in

clockwise direction, winds the motor. Counterclockwise movement is prevented by means of ratchet stop 19. The key handle 20 is pivoted to permit of its being turned flat against casing 10 in the recess 21 therein provided.

The gear train 13 is also affixed to the casing in the usual manner. It consists of the usual series of gear wheels 22 and pinions 23 mounted on shafts 24. The first of its pinions 23a meshes with large gear wheel 25 of spring motor 11. The last of its gear wheels 22a meshes with pinion 26 affixed to the shaft 27 of dynamo 12. Gear wheel 22a has outer gear teeth 28, side or beveled gear teeth 29 and internal gear teeth 30.

The combination gear speed changer and electric switch 16 comprises a notched shaft 31 to which is affixed a fork 32. A block 33 affixed to the casing and having two borings 34 formed therein, receives the fork 32. A cylindrically shaped member 35 integral with or affixed to said casing opposite said block 33 receives the shaft 31, said shaft projecting outwardly from said casing through aperture 36 registering with member 35. Longitudinal movement of said changer and switch 16 along its own axis is thereby permitted. Affixed to the projecting end of shaft 31 is a knob or button 37. Formed in said shaft between said casing and said button are three notches 38. Slidably affixed to the outer casing wall adjacent said notches is a tongue 39 which, when moved toward said shaft 31 engages said notches 38. Movement in the direction away from said shaft 31 disengages said tongue from said notches.

Affixed to said shaft adjacent said cylindrically shaped member 35 is a governor 40 having beveled gear teeth 41. Affixed to said shaft at the point where shaft and fork meet is a finger 42 whose function will shortly be described. Affixed to the upper prong of fork 32 is a block 43 made of material that does not conduct electricity. Affixed to block 43 by means of screw 44 is resilient contact member 45. A plate 46 made of similar material and carrying terminals 47 and 48 is affixed to block 33.

Small flashlight bulb 14 is screwed into socket 49 in casing 10 and large flashlight bulb 15 is screwed into socket 50 in said casing.

Lenses 51 and 52 close said sockets and expose said bulbs in the usual way.

As shown in Figure 5 a wire conductor 53 connects bulb 14 with bulb 15. Another wire conductor 54 connects bulb 14 with terminal 47 and still another wire conductor 55 connects bulb 15 with terminal 48. The dynamo 12 is connected

by means of wire conductor 56 to wire conductor 53 and by means of wire conductor 57 to contact member 45.

The device hereinabove described operates as follows: key 18 is turned in a clockwise direction thus winding the spring motor 11. The motor causes large gear wheel 25 to rotate and said wheel, being in mesh with pinion 23a of gear train 13, causes rotation of each and all of the gear wheels 22 and pinions 23 of said gear train. Gear wheel 22a of said gear train, being in mesh with pinion 26 affixed to the shaft 27 of dynamo 12, causes the dynamo to rotate. Since the gear train, as can be seen in Figure 1 is a step-up gear train—speed increasing gearing as distinguished from reduction gearing—the speed of rotation of the dynamo will be greater than the speed of rotation of large gear wheel 25 of spring motor 11. The speed of rotation of dynamo 12 may be controlled in the following way: The dynamo may be allowed to run freely. Its speed of rotation would thereby be the highest the spring motor is capable of inducing. This of course would enable the dynamo to generate the maximum amount of electrical current per unit of time. To provide for free running of the dynamo, gear speed changer and electric switch 16 is moved inwardly from its position in Figure 5 to the first dotted position 60. To hold it in that position tongue 39 is caused to engage the middle notch of notches 38. When gear speed changer and electric switch 16 is held in this neutral position, neither its finger 42 nor its governor 40 is in contact with any other part of the mechanism. Contact member 45, however, is brought into contact with terminal 48 thus closing the circuit between said dynamo and large bulb 15.

The dynamo may be held to a reduced speed of rotation to produce a reduced amount of electrical current per unit of time. The total amount of current would substantially approximate the total current produced when the dynamo is allowed to run freely, but it would be doled out over a longer period of time. The way to reduce the speed of the dynamo is to cause governor 40 to engage gear wheel 22a of gear train 13. Tongue 39 is caused to disengage notched shaft 31. The shaft is moved inwardly to dotted position 61 shown in Figure 5 and tongue 39 is caused to engage the last notch, to wit, the notch nearest knob or button 37. The assumption of position

61 by shaft 31 causes beveled gear teeth 41 of governor 40 to engage beveled gear teeth 29 of gear wheel 22a. In addition contact member 45 is made to engage terminal 47 thus breaking the circuit between the dyanmo and large bulb 15 and making the circuit between the dynamo and small bulb 14.

The dynamo may be brought to a stop by the simple device of disengaging tongue 39 and pulling gear speed changer and electric switch 16 out until finger 42 is brought into engagement with internal gear teeth 39 of gear wheel 22a. To maintain gear speed changer and electric switch 16 in this position, position 62 as shown in Figure 5, tongue 39 is made to engage the first of notches 38, to wit, the notch nearest casing 10.

The mechanism herein disclosed is only an embodiment of the invention. Modifications, additions and subtractions are herein contemplated although they are not specifically shown. For example the combination gear speed changer and electric switch might be modified to provide for free running speed of dynamo 12 when in position 62 and for a complete stoppage of rotation of said dynamo when in position 61. This may be accomplished by changing the positions of finger 42 and terminals 47 and 48. Another change might consist in eliminating one of the two bulbs and providing for use by the remaining bulb of either the weaker or the stronger current generated by the dynamo.

I claim:

A self-generating flashlight comprising a current generating mechanism which selectively generates currents of different strength, a plurality of light bulbs of different voltage each being in a different circuit, and selective means to direct the different currents into the different circuits, said generating mechanism consisting of a spring motor, a dynamo, a train of speed increasing gears connecting said motor with said dynamo, and a combination gear speed changer and electric switch comprising a governor adapted to engage said gear train, means for selectively making and breaking the circuits of the different bulbs and means carrying said governor and selective making and breaking means adapted to coordinate the engaging and disengaging of said governor with the selective making and breaking of said circuits.

HENRY WELL.
